UNITED STATES PATENT OFFICE.

LEE R. TALBERT, OF LONG BEACH, CALIFORNIA.

SASH-CORD GUIDE.

Application filed January 5, 1926. Serial No. 79,320.

This invention relates to improvements in sash cord guides primarily designed to be used in connection with window constructions.

5 An object of this invention is to provide a sash cord guide of novel construction, which is adapted to be mounted in a window frame and support the sash cord where it passes through the window frame in connecting the counterweight to the window sash.

Another object of this invention is to provide a sash cord guide of cheap, simple and durable construction which may be used in a window frame and which will replace or 15 serve the same function provided by the usual pulley.

With the foregoing and other objects in view which will be made manifest in the following detailed description and specifically 20 pointed out in the appended claim, reference is had to the accompanying drawings for an illustrative embodiment of the invention, wherein:

Figure 1 is a partial side elevation, parts 25 being broken away, illustrating a portion of a window on which the improved guide has been mounted,

Fig. 2 is a vertical section taken substantially on the line 2—2 of Fig. 1,

30 Fig. 3 is a top plan view of the guide,

Fig. 4 is a vertical section taken substantially on the line 4—4 of Fig. 3, and

Fig. 5 is a view in end elevation of the 35 guide and may be considered as taken in the direction of the arrow 5 on Fig. 3.

Referring to the accompanying drawings wherein similar reference characters designate similar parts throughout, the window frame is indicated generally at F, in which 40 two sash S and S' are slidable. Sash cords C connect their respective sash to counterweights W which are housed within the frame F. The improved sash cord guide consists of a tube 10 of sufficient length so 45 that it can extend completely through the window frame F. On the ends of the tube at the bottom thereof there are provided two tongues 11 and 12. These tongues are bent upwardly and inwardly so that their ends 50 extend toward the interior of the tube and

are transversely bent so as to present upper concave surfaces on which the sash cords C are adapted to rest. These tongues therefore provide a support for the sash cord so as to support it above the bottom of the tube 55 10. On one end of the tube 10 there is provided a flange 13 which may be welded or otherwise secured to the tube. This flange has apertures 14 formed in it for the reception of screws in mounting the device upon 60 a window frame. If desired, a strip of metal 15 may be fastened to or positioned against the under side of the tube, this strip extending from the lower portion of one tongue to the lower portion of the other and 65 serving as a reinforcement for the tongues.

In mounting the improved sash cord guide on a window frame, it is merely necessary to bore a hole through the frame and insert the tube 10 in it, afterwards driving screws 70 through the apertures 14 in the flange 13. The sash cord can then be threaded through the tube and positioned on top of the tongues 11 and 12, it being retained on top 75 of these tongues because of the concave surfaces which they present.

From the above described construction it will be readily appreciated that an improved form of sash cord guide is provided which is of cheap, simple, yet durable construction, 80 and will efficiently guide the sash cord during the raising or lowering of the sash.

It will be understood that various changes in the detail of construction may be made without departing from the spirit or scope of 85 the invention as defined by the appended claim.

I claim:

A sash cord guide comprising a tube adapted to be mounted in a window frame 90 and through which a sash cord is adapted to pass, and tongues formed upon the ends of the bottom of the tube which are bent upwardly and inwardly with their ends extending toward the interior of the tube, said 95 tongues presenting concave upper surfaces on which a sash cord is adapted to rest.

In testimony whereof I have signed my name to this specification.

LEE R. TALBERT.
